UNITED STATES PATENT OFFICE

162,445

SERVING DISH OR THE LIKE

Roscoe J. Pastory, Dallas, Tex.

Application November 22, 1949, Serial No. 6,189

Term of patent 3½ years

(Cl. D44—10)

To all whom it may concern:

Be it known that I, Roscoe J. Pastory, a citizen of the United States, residing at Dallas, in the county of Dallas, State of Texas, have invented a new, original, and ornamental Design for Serving Dish or the Like of which the following is a specification, reference being had to the accompanying drawing, forming part thereof.

In the drawing, which illustrates the new ornamental design:

Figures 2 and 4 are, respectively, side and end elevational views; and

Figures 3 and 5 are sectional views thereof taken, respectively, on lines 3—3 and 5—5 of Figure 1.

I claim:

The ornamental design for a serving dish or the like, as shown.

ROSCOE J. PASTORY.
